RAILROAD ENGINEMAN'S CLEAR VISION
WINDOW

William McMinnis, Elkhart, Ind.

Application March 18, 1943, Serial No. 479,628

3 Claims. (Cl. 20—40)

The present invention relates to new and useful improvements in enginemen's clear vision windows for railroad engine cabs, and has for its primary object to provide, in a manner as hereinafter set forth, a device of this character comprising a novel construction and arrangement whereby various sizes of clear vision openings at different elevations or positions may be conveniently had.

Another very important object of the invention is to provide, in a clear vision window of the aforementioned character comprising a frame and a plurality of panes mounted for vertical sliding movement therein, unique means for holding said panes in adjusted position.

Still another very important object of the invention is to provide an enginemen's vision window of the character described wherein the panes may be expeditiously removed from the frame from the inside of the cab for cleaning or other purposes.

Other objects of the invention are to provide an enginemen's clear vision window which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a window constructed in accordance with the present invention mounted in position on a railroad engine cab.

Figure 2 is a view in front elevation of the window, showing two of the panes elevated to provide a clear vision opening.

Figure 3 is a view in vertical section through the window.

Figure 4 is a view in horizontal section, taken substantially on the line 4—4 of Figure 2.

Referring now to the drawings in detail, it will be seen that the embodiment of the invention which has been illustrated comprises a frame of suitable dimensions and material which is designated generally by reference numeral 1. The frame 1 is secured in any desired manner in the usual opening provided therefor in the front 2 of a railroad engine cab 3.

The frame 1 includes top, bottom and side members 4, 5 and 6, respectively. The bottom

and side members 5 and 6 are formed to provide channels or grooves 7 for receiving vertically slidable panes 8 which are removably mounted in the frame. The side members 6 of the frame 1 include extensions 9 on their upper ends which project above the member 4.

Vertical rods 10 are mounted on the side portions of the frame 1 inwardly of the latter. Brackets 11 on the frame 1 receive the end portions 10 of the vertical rods 10. Comparatively large and small plates 12 and 13, respectively, are mounted for sliding and swinging movement on the rods 10. The plates 12 and 13, which are engageable between the panes 8, or 15 beneath the lowermost of said panes, include eyes 14 which are rotatable and slidable on the rods 10.

It is thought that the manner in which the window functions will be readily apparent from 20 a consideration of the foregoing. Briefly, when no clear vision opening is desired, the panes 8 are in the position shown in Figure 1 of the drawings and the members 12 and 13 are not in use. If a clear vision opening is desired, however, 25 it is only necessary to elevate one or more of the panes 8 and engage either or both of the members 12 and 13 therebeneath, as suggested in Figure 3 of the drawings. It will thus be seen that the opening may be had at substantially any desired elevation and, further, the comparatively large and small plates 12 and 13 permit openings of different sizes to be had. The channels or 30 grooves 7 are open at the upper ends of the side extensions 9. This permits the panes 8 to be 35 readily removed for cleaning from the inside of the cab.

It is believed that the many advantages of a railroad enginemen's clear vision window constructed in accordance with the present invention 40 will be readily understood, and although a preferred embodiment of the device is as illustrated and described, it is to be understood that changes in the details of construction and in the combination and arrangement of parts may be 45 resorted to which will fall within the scope of the invention as claimed.

What is claimed is:

1. A railroad enginemen's clear vision window comprising a frame, a plurality of panes mounted 50 for vertical sliding adjustment in said frame, vertical rods mounted on the frame, and members pivotally and slidably mounted on the rods and engageable selectively beneath or between the panes for providing an unobstructed opening 55 in the window at various elevations.

2. A railroad enginemen's clear vision window comprising a frame including top, bottom and side members, said side members including extensions projecting above the top member, the bottom and side members having channels therein open at their upper ends, a plurality of panes mounted for vertical sliding adjustment in the channels, vertical rods mounted on the side portions of the frame, and a plurality of plates mounted for swinging and sliding movement on the rods, said plates including eyes journaled on the rods, said plates being engageable selectively beneath or between the panes for providing an unobstructed opening in the window at various elevations.

3. A window comprising a grooved frame providing a window opening, a plurality of more than two horizontally elongated panes vertically slideable in said frame and independently movable to selectively provide a space between any 20

two adjacent panes or between the lowermost pane and the bottom of the frame, said panes being in the same vertical plane and normally disposed in edge-to-edge abutting relation to close the window opening with the lowermost pane resting in the bottom of the frame, vertical guide rods mounted on and extending from top to bottom of the frame at opposite sides of the latter, and a pair of superposed independently movable prop members of different heights slidably and pivotally mounted on each guide rod, said prop members being vertically adjustable and selectively swingable horizontally to project between the opposite ends of the panes or between the ends of the lowermost pane and the bottom of the frame, whereby a space of either of the different heights may be selectively provided at the top or bottom or intermediate the top and bottom of the frame.

WILLIAM McMINNIS.
